UNITED STATES PATENT OFFICE.

JOHN WOOL GRISWOLD, OF TROY, NEW YORK.

BARBED-WIRE FENCE.

SPECIFICATION forming part of Letters Patent No. 465,642, dated December 22, 1891.

Application filed June 15, 1891. Serial No. 396,258. (No model.)

To all whom it may concern:

Be it known that I, JOHN WOOL GRISWOLD, of Troy, Rensselaer county, New York, have invented a new and useful Improvement in 5 Barbed-Wire Fences, of which the following is a specification.

My invention relates to that class of wire fencing which is composed of a series of links, usually barbed; and it consists in the construction of said links and their combination to form a continuous fencing.

In the accompanying drawings, Figure 1 is a plan view of my improved wire fencing. Fig. 2 is a side view, and Fig. 3 is an end view 15 of the link *a*, showing the parallel eyes *C* and *D*.

Similar letters of reference indicate like parts.

Each link *ab* consists of a length of wire *A*, 20 doubled or halved on itself to form at one end of said link the eye *B*. One end of the doubled-over wire *A* is bent to form the eye *C*. The other end of the doubled-over wire *A* is bent in like manner to form the eye *D*. The two 25 eyes *C* and *D* are placed side by side, as shown. The extremities *E F* of the wire *A* are locked or twisted together on one side of the main portion of the link *a* and are then bent outwardly to form barbs.

In uniting the links the eye *B* of one link, 30 as *b*, engages with the eyes *C D* of the other link *a*.

This fencing is strong, durable, and easily and cheaply made.

I claim—

1. A wire-fencing link composed of a length of wire doubled to form a loop or eye *B* at one extremity of the link and having its ends bent over to form eyes *C D*, the extremities *E F* of said wire being locked or twisted together on one side of said link and protruding to form barbs. 35

2. A wire-fencing composed of a series of enchain'd links, each link being composed of a length of wire doubled to form a loop or eye 40 *B* at one extremity of the link and having its ends bent over to form eyes *C D*, the extremities *E F* of said wire being locked or twisted together on one side of the link and protruding to form barbs, and the eye *B* of one link 45 engaging with the eyes *C D* of the next adjacent link. 50

JOHN WOOL GRISWOLD.
